UNITED STATES PATENT OFFICE.

SIMEON COFSKY, OF MONTREAL, QUEBEC, CANADA, ASSIGNOR TO LYMBURNER
LIMITED, OF MONTREAL, CANADA.

MACHINE FOR SCREWING SOCKETS AND THE LIKE.

1,188,626.

Specification of Letters Patent. Patented June 27, 1916.

Application filed August 9, 1915. Serial No. 44,580.

To all whom it may concern:

Be it known that I, SIMEON COFSKY, a subject of the King of Great Britain, and residing in the city of Montreal, in the Province of Quebec, in the Dominion of Canada, have invented certain new and useful Improvements in Machines for Screwing Sockets and the like; and I do hereby declare that the following is a full, clear, and

exact description of the same.

The invention relates to a machine for screwing sockets and the like and more particularly brass sockets on shells and the object of the invention is to devise a machine which will screw the brass sockets on shells rapidly, thereby economizing in the cost of manufacture and saving hands to do it.

A further object is to devise a machine that will screw these sockets tightly and once the machine has been set, it is so easy to operate that it can be worked by a boy or unskilled person.

The invention will be fully understood with the aid of the accompanying drawings 25 in which—

Figure 1 is a side elevation of the machine. Fig. 2 is a longitudinal cross sectional view of the machine. Fig. 3 is a top view of the machine. Fig. 4 is a top view 30 of the machine showing the worm and gear in section.

Like numerals of reference indicate corresponding parts in each figure.

Referring to the drawings, 1 is a casing 35 having an inwardly projecting flange 2 and supporting legs 3 and 4 is a covering plate having a central orifice 5.

6 is a supporting table on which is secured the said casing 1. 40 7 is a chuck having the central bore 8, tapered at its outward end 9, and 10 is an outwardly and downwardly projecting stub, threaded at 11.

12 is an orifice through said projecting 45 stub 10 and 13 is an outwardly projecting flange intermediate of the height of said chuck 7 abutting under the flange 2 in the casing 1 and secured thereto.

14 is a gear rigidly secured to the collar 50 15, said collar being loosely mounted on the upper end of said chuck 7 and resting on the flange 2 and 16 is a stop collar secured

around the outward end of the chuck above said collar 15.

17 are posts or lugs secured to said collar 55 15 and outwardly projecting therefrom engaging the pawls 18 which are pivotally mounted on the ring 19 at 20, said pawls having the eccentric heads 21 which slightly project inwardly through the central orifice 60 22 in the ring 19.

23 is an inner chuck loosely fitting in said chuck 7 having at its outward end a corresponding tapered end 24 and 25 is an orifice in which passes the tube 26, said tube having 65 the head 27 projecting inside said inner chuck and thread 28 on which is threaded the nut 29, thus firmly clamping the bottom of the inner chuck, the other end of said tube being of a smaller diameter and also 70 threaded at 30.

31 is a hand wheel having the partial central bore 32 one end of which is opened and inwardly threaded at 33, said thread engaging the thread 11 on the lower end 75 of the chuck 7, the other end being provided with an orifice 34 and 35 is a collar mounted on said smaller diameter tube, abutting against the shoulder formed by the larger diameter of the said tube 26 and resting 80 against the bottom of said bore 32 and 36 is a nut engaging the thread 30 on the end of the tube 26 and rigidly securing the hand wheel 31 on said tube 26. The said inner chuck 23 is longitudinally slotted at different intervals therearound so that it may have some elasticity and therefore grip the shell 37 more firmly and 38 is a circumferential depression intermediate of the length 85 of said chuck 23, so as to avoid friction. 90

39 is a bushing having a central perforation of identically the same shape as the upper end of the shell adapted to protect the copper band on the shell, also to lock said shell in the chuck 23.

95 40 is a rod in said tube 26 and 41 is a foot lever, fulcrumed at 42 and actuating said rod upwardly to push the shell out of the chuck when the cap 43 has been screwed. The shell is first placed in the chuck and rests on the head 27 of the tube 26, in the bottom of the inner chuck 23, the bushing 39 is then placed on said shell between the side of said chuck and shell and the hand

wheel 31 is turned thereby pulling the chuck 23 downwardly and locking the shell 37.

44 is a worm mounted on the shaft 45 engaging the gear 14 and 46 is a pulley mounted on one end of said shaft 45 the other end being suitably supported by the bearings 47 in the side of the casing 1.

48 is a lever pivotally secured to one end of the shaft 49, said shaft being supported 10 by the bracket 50 secured to the casing 1 below the worm 44 and loosely revolving therein.

51 is a bracket secured to the other end of said shaft 49, shown in dotted lines, supporting the tightening pulley 52 which contacts with the belt 53 when the lever 48 is pulled inwardly thereby regulating the driving power of the machine at will.

After the shell has been set in the chuck 20 as described above, the threaded cap 43 is placed on the end of the shell 37 and the ring 19 is placed on said cap 43, the central orifice 22 engaging one side of said cap. The lever 48 is pulled to give the driving 25 power to the machine, and the worm mounted on the shaft 45 rotates the gear 14, the gear 14 rotates the collar 15 and the posts 17. In revolving, the posts or lugs 17 come in contact with the pawls 18 and slightly tip 30 them which causes the eccentrics 21 to engage the sides of the cap 43 and lock same. When the operation of screwing the cap is terminated, the ring 19 and the bushing 39 are removed and the hand wheel unscrewed, 35 thereby unjamming the shell from the chuck 23 and the foot lever 41 is pressed, pushing the rod 40 forward and lifting out the shell from the chuck.

The operation of the invention, as will 40 be seen, is most simple and it does not require skilled hands to work this machine.

It must be understood that the constructional details of the herein described invention can be modified, if found desirable, so 45 long as I do not depart from the invention as claimed in the following claims for novelty.

What I claim is:

1. In a machine for screwing sockets on 50 shells or the like comprising the casing, a chuck supported in said casing adapted to receive the shell, means to lock said shell in said chuck, a ring centrally bored over said shell, means to grip the cap or socket 55 in said ring and means to revolve said ring substantially as described.

2. In a machine for screwing sockets on 60 shells and the like, comprising a casing suitably supported having a central aperture, a chuck in said aperture, a flange on said chuck abutting to a flange on the inner side of the casing and secured thereto, said chuck having a downwardly projecting end centrally bored and threaded on the outside, 65 a hand wheel registering on said thread, a

rod secured to said hand wheel projecting through the central hole in the end of the chuck, an inner chuck secured thereto and registering in said above mentioned chuck, means to secure the shell in said inner chuck, 70 and means to screw the socket or cap substantially as described.

3. In a machine for screwing sockets on shells and the like, comprising a casing suitably supported and having a central aperture, an exterior chuck supported in said central aperture, said chuck having its upper inner end tapered and having an orifice in the bottom thereof, an inner chuck fitting snugly in said outer chuck, the upper end having a corresponding taper to that of the inner end of said outer chuck and registering, said inner chuck having a central depression around the outside intermediate of its length, and an orifice in the bottom thereof corresponding to the orifice in the bottom of the outer chuck, a rod centrally bored passing through said orifices, a head at one end of said rod forming a shoulder and resting on the bottom of said inner chuck, a nut threaded on said rod rigidly securing said inner chuck, a hand wheel having its axis centrally and partially bored, an orifice in the bottom of said central bore corresponding to the orifice in the bottom of said outer chuck, said rod projecting through said orifice and forming a shoulder against which the bottom of said central bore is secured by a screw threaded on the end of said rod, said hand wheel being 100 threaded on the bottom of said outer chuck, a bushing registering over said shell secured between the inner side of the inner chuck and the shell casing, means to secure the cap or socket on said shell and means 105 to screw said cap or socket substantially as described.

4. In a machine for screwing sockets and the like, comprising a casing, a chuck secured in said casing, means to secure a shell 110 within said chuck, a ring centrally bored over said shell, pawls pivotally mounted on said ring slightly projecting within said central bore in said ring, a collar loosely mounted around said chuck, lugs projecting upwardly from said collar engaging the pawls on said ring, means to revolve said collar and ring in order that the pawls will close and grip the cap or socket on said shell substantially as described.

5. In a machine for screwing sockets and the like, comprising a casing, a chuck secured in said casing, means to secure a shell within said chuck, a ring centrally bored fitting over said shell, pawls projecting outwardly from said ring and pivoted around said central bore, the ends of the pawls slightly projecting inwardly in order to grip the socket or cap on said shell, a collar mounted around said chuck and revolv- 125 130

ing thereon, lugs projecting upwardly from said collar engaging the pawls on said ring, a band around said chuck above said collar secured to said chuck, a gear mounted 5 around said chuck secured to said collar, a worm actuating said gear and means to drive said worm substantially as described.

Signed at Montreal, Quebec, Canada, this 8th day of July, 1915.

SIMEON COFSKY.
